UNITED STATES PATENT OFFICE.

CHARLES H. CROWLEY, OF NEW YORK, N. Y.

CROCHET-BALL HOLDER.

1,208,502.

Specification of Letters Patent. Patented Dec. 12, 1916.

Application filed November 11, 1914. Serial No. 871,602.

To all whom it may concern:

Be it known that I, CHARLES H. CROWLEY, a citizen of the United States, residing at New York, in the county of New York, 5 State of New York, have invented certain new and useful Improvements in Crochet-Ball Holders; and I do hereby declare the following to be a full, clear, and exact description of the invention, such as will enable others skilled in the art to which it appertains to make and use the same.

This invention relates to a crochet ball holder.

An object of the invention is to provide 15 a device by means of which crochet balls may be held on the user's wrist so that the ball will not in any way impede the operation of crocheting and which will be wound in such manner that the yarn may be readily 20 and easily drawn therefrom without the conscious operation of the user.

A further object of the invention is to so construct the device that all possibility of the yarn becoming broken or marred will 25 be entirely obviated.

With these and other objects in view, such as will appear as the description progresses, my invention comprises the combination and arrangement of parts as set forth in and 30 falling within the scope of the appended claim.

Referring to the drawing: Figure 1 is a side elevation of my device. Fig. 2 is a fragmental detail showing the construction 35 of the ends of the ball holder and the swivel.

Referring to the drawing wherein like parts are indicated by like characters throughout the several views:—My device comprises a wrist band 1 which is made of 40 a continuous piece of spring wire wound in any desired formation. Through this wrist band extends a limiting member 2 so that the said wrist band may not be stretched so far that the resiliency of the wire will be 45 destroyed. Secured to this band 1 is an eye 3 to which eye is secured a swivel 4 on the other end of which is a swivel ring 5.

In order that the yarn may be wound into a ball and that it may be freely unwound 50 from the said ball without catching, I have secured to the ring 5 a member 6 having a shank portion 7 and arms 8, 9 and 10, the arms 8 and 10 extending at right angles to the shank portion and the arm 9 in alinement therewith. This member 6 is constructed entirely of one piece of wire. The

yarn is first wound in the space between the shank portion 7 and the arm 8, then in the space between the arms 8 and 9, then in the space between the arms 9 and 10, and finally 60 in the space between the arms 10 and the shank portion 7, and the winding operation continues in this manner to form a round ball.

First an eye 11 is formed in one end of 65 the wire which is engaged with the ring 5 and the wire is then extended to form a portion of the shank 7 and bent outwardly at right angles and then back on itself to form the arm 8, it is then bent at right angles to 70 this last mentioned arm and in alinement with the shank 7 and back on itself to form the arm 9, the wire is then continued at right angles to the arm and in alinement with the arm 8 and back upon itself to form 75 the arm 10. Finally it is bent at right angles to the arms 8 and 10 and extended to form the other portion of the shank and has an eye 12 formed in this end, which is likewise in engagement with the ring 5 as 80 will be readily seen from the drawing. It may be thus seen that as the yarn is wound upon the device diagonally around the arms 8, 9 and 10 and the shank 7 that the parts on which it is wound will be entirely smooth 85 and there will be no corners in which the yarn may catch and thus when the yarn is unwound from the device during the operation of crocheting it will move very readily and without in any way being caught. 90

From the foregoing description it may be seen that I have provided a device by means of which a crochet ball may be held so that the yarn constituting the ball will not become tangled or marred or broken during 95 the operation of either winding or unwinding, and I have so constructed the device that the yarn will be readily unwound therefrom without conscious effort upon the part of the user. 100

While I have illustrated and described a particular embodiment of my invention, I have merely done so for the sake of convenience and I wish it to be understood that I do not wish to be limited to that particular 105 embodiment as it is obvious that numerous changes may be made in the details of construction thereof without in any way departing from the spirit of the invention or exceeding the scope of the appended claim. 110

What I claim is:—

A yarn holder including a body member

formed from a single length of wire bent intermediate its ends to provide juxtaposed portions forming the lower limb of a cross, each end of said wire being then bent outwardly at right angles to the first portions and rebent inwardly to provide juxtaposed portions forming the arms of said cross, each end of the wire being then bent upwardly to provide coacting juxtaposed portions forming the upper limb of the cross, the extremities of said wire being bent to

form eyes one of which overlaps the other in coaxial relation, and a swivel supporting means including a ring passing through both of said eyes to prevent spreading of 15 said wire ends.

In testimony whereof, I affix my signature, in the presence of two witnesses.

CHARLES H. CROWLEY.

Witnesses:

WILLIAM S. HARRIS,
I. VAN GELDER.
